UNITED STATES PATENT OFFICE.

CHARLES A. BLUHM, OF MICHIGAN CITY, INDIANA.

VENTILATED WATER-CLOSET.

SPECIFICATION forming part of Letters Patent No. 470,740, dated March 15, 1892.

Application filed June 24, 1891. Serial No. 397,308. (No model.)

To all whom it may concern:

Be it known that I, CHARLES A. BLUHM, a citizen of the United States, residing in Michigan City, in the county of La Porte and State 5 of Indiana, have invented a new and useful Improvement in Ventilated Water-Closets, of which the following is a specification.

My invention relates to water-closets.

The object of my invention is to provide a 10 closet with means for ventilating the same and conveying away gases, fumes, or odors which tend to arise when the closet is in use, and whereby at the same time the person of the occupant will not be subjected to disagreeable drafts, to the end that all odors and fumes may be prevented from escaping into the room.

My invention consists, in combination with the closet-bowl, of a seat furnished with a 20 hollow chamber or passage having openings through its bottom communicating with the bowl and connected with an air-escape or exhaust flue or pipe, whereby the fumes and gases in the bowl may escape.

It also consists, in connection with such 25 hollow seat, bowl, and air-escape pipe or flue, in furnishing the hollow seat with an air-inlet passage to admit free air to the bowl and cause an air-circulation through the same and 30 through the hollow seat, and at the same time protecting the person of the occupant from disagreeable drafts.

It also consists in the novel devices and 35 novel combination of parts and devices herein shown and described, and more particularly pointed out in the claims.

In the accompanying drawings, which form 40 a part of this specification, and in which similar letters of reference indicate like parts, Figure 1 is a central vertical sectional view of a device embodying my invention. Fig. 2 is a plan or sectional view, looking from the line 2 2 of Fig. 1. Fig. 3 is a vertical section on the line 3 3 of Fig. 1, and Fig. 4 is a detail 45 view of the valve.

In the drawings, A represents a closet-bowl, which may be of any well-known or suitable construction.

B is the closet-seat, hinged in the usual

manner to the stationary frame C, that is 50 supported on the bracket D.

E is the hinged cover of the seat.

The seat B is furnished with a hollow chamber or passage b, preferably extending entirely around the seat-rim, which overhangs 55 the rim or lip a of the bowl A. Leading through the bottom wall of the hollow seat are air passages or openings b', which communicate with the interior of the bowl, and one or more air passages or openings b² lead 60 from the outside of the bowl into the annular chamber b to admit the fresh air into the same and thence into the bowl, as indicated by the arrows in Fig. 1. The chamber or passage b in the hollow seat communicates at the 65 rear or hinged end of the seat with a similar passage c in the stationary part or frame C. When the seat is down, as shown in Fig. 1, a continuous passage or chamber b-c will thus be formed in the seat B and frame C, and this 70 air-passage b-c communicates with the ventilating pipe or flue F. An intermediate ornamental box or chamber G may preferably be interposed between the pipe or flue F and the stationary part or frame C. 75

To make a close or tight connection between the hinged hollow seat and the bowl A, I provide the former with a rubber gasket or ring b³. The annular chamber or passage b in the hollow seat I likewise preferably provide with valves b⁴ b⁴. When these valves are closed, the air admitted at the inlet-port b² will be forced down through the openings b' at the front portion of the seat into the bowl, and will thence pass out through the 85 openings b' at the rear portion of the seat. When the valves b⁴ are open, the air, passing into the hollow seat at b², may pass directly through the hollow seat or rim and out through the exhaust-pipe F without passing through 90 the bowl. In this latter case the current of air through the hollow seat will, however, by its exhaust action draw the air and gases from the bowl into the hollow seat, and thence out. The ventilating-pipe F may communicate with the smoke or other flue of the 95 building or may be carried directly out through the roof. When the hinged cover E

is down or closed, there is a continuous air-passage for the ventilation of the bowl in through the inlet-port b^2 , through the hollow chamber b of the seat-openings b' , into the bowl, and out through the openings b' at the rear of the seat-passages b c, through the ventilating-pipe F.

I claim—

1. The combination, with closet-bowl A, of hollow hinged seat B, having openings communicating with said bowl, hollow frame C, to which said seat is hinged, the air-passage in said frame communicating with the air-passage in said seat when the latter is down, and a ventilating-pipe F, communicating with said hollow frame, substantially as specified.
2. The combination of closet-bowl A with hinged seat B, having chamber b and openings b' and b^2 , the former communicating with the interior of the bowl and the latter outside of the same, and a ventilating pipe or flue communicating with said chamber b , substantially as specified.
3. The combination of closet-bowl A with

hinged seat B, having chamber b and openings b' and b^2 , the former communicating with the interior of the bowl and the latter outside of the same, a ventilating pipe or flue communicating with said chamber b , and valves b^4 , arranged in said chamber or passage b , substantially as specified.

4. The combination, with closet-bowl A, of hollow hinged seat B, having chamber b extending around the same and furnished with openings b' , leading into the bowl, and air-inlet passages b^2 , leading outside of the bowl, frame C, having hollow chamber or air-passage communicating with said chamber or passage b , ventilating-flue F, communicating with said air-passage b c, hinged cover E, and a box or chamber G, interposed between said ventilating-flue F and said frame C, substantially as specified.
